United States Patent Office

Des. 221,515
Patented Aug. 24, 1971

221,515

JUG

Harold A. Betka, Waukegan, Ill., assignor to
Abbott Laboratories, North Chicago, Ill.

Filed Feb. 16, 1970, Ser. No. 21,443

Term of patent 14 years

Int. Cl. D9—01

U.S. Cl. D9—40

FIG.4

FIG.1

FIG.3

FIG.2

FIG.5

FIG. 6

FIG. 1 is a perspective view of a jug showing my new design;

FIG. 2 is another perspective view;

FIG. 3 is a perspective view showing the side opposite that seen in FIG. 2;

FIG. 4 is a top plan view;

FIG. 5 is a bottom plan view; and

FIG. 6 is a side elevational view thereof.

I claim:

The ornamental design for a jug, substantially as shown.
